CLAIM

The ornamental design for a state-shaped lamp, as shown and described.

DESCRIPTION

FIG. 1 is a perspective view of the state-shaped lamp;
FIG. 2 is another perspective view of the state-shaped lamp;
FIG. 3 is a left side view of the state-shaped lamp;
FIG. 4 is a right side view of the state-shaped lamp;
FIG. 5 is a front view of the state-shaped lamp;
FIG. 6 is a rear view of the state-shaped lamp;
FIG. 7 is a top view of the state-shaped lamp; and,
FIG. 8 is a bottom view of the state-shaped lamp.

In FIG. 1 the perspective view of the state-shaped lamp also shows a dotted line drawing of the cable. It is to be understood that this is not part of the invention but only shown for illustrative purposes only and forms no part of the claimed design.
